UNITED STATES PATENT OFFICE.

CHARLES H. CLOWER, OF PHILADELPHIA, PENNSYLVANIA, ASSIGNOR TO CRUSE-KEMPER COMPANY, OF AMBLER, PENNSYLVANIA, A CORPORATION OF PENNSYLVANIA.

GAS-PURIFYING APPARATUS.

1,177,586.

Specification of Letters Patent.

Patented Mar. 28, 1916.

Application filed July 3, 1915. Serial No. 37,801.

To all whom it may concern:

Be it known that I, CHARLES H. CLOWER, a citizen of the United States, and a resident of the city of Philadelphia, county of Philadelphia, State of Pennsylvania, have invented certain new and useful Improvements in Gas-Purifying Apparatus, of which the following is a specification.

In gas or vapor purifying apparatus as heretofore constructed it has been a difficult and expensive matter to remove the iron oxid from its containers after the same has been used. The practice heretofore has been for a workman to enter a chamber with a pick or other implement and loosen up the more or less granular material and remove the same in small portions.

It is one of the objects of my invention to avoid this expensive operation by providing an apparatus in which the container for the iron oxid which is used to remove impurities from the gas may be removed from its inclosing chamber and the iron oxid discharged or removed therefrom quickly and with a minimum amount of labor.

A further object of my invention is to provide an improved construction of container by the employment of which the amount of iron oxid purifying material required is reduced and the purification of the gas or vapor passing through the purifying material therein is facilitated.

A still further object of my invention is to provide an improved construction of container,—one which may be readily collapsed and thereby reduce to a minimum the cost of discharging or removing the compact and hard purifying material therefrom.

Other objects and advantages of my invention will be referred to and pointed out in the detailed description thereof which follows or will be apparent from such description.

In order that my invention may be more readily understood and comprehended reference should be had to the accompanying drawings in which I have illustrated one form of a convenient embodiment thereof but it will be understood that changes in the details of construction and in the arrangement of parts may be made within the scope of the claims appended hereto without departing from my invention.

In the drawings:—

Figure 1 is a view partly in vertical sec-

tion and partly in side elevation of an apparatus embodying my invention; Fig. 2 is a view partly in vertical section and partly in elevation taken at right angles to the view shown in Fig. 1; and Fig. 3 is a section view taken on the line 3—3 of Fig. 1 showing a detail of construction.

Referring to the drawings, 1 designates a base or foundation of suitable construction on which the apparatus is supported and 2 designates an inclosure or casing within which the iron oxid container and other apparatus, to which reference will be hereinafter made, are situated. As is apparent from Fig. 2 of the drawings the casing or inclosure is divided into compartments separated by transversely extending plates, such as 3, and within each of these compartments the containers for holding purifying material and other apparatus are situated. The gas purifying material is held in containers which respectively comprise side frame structures which are adapted to be detachably secured together so that they may be readily separated to thereby facilitate the discharge and removal of the condensed and compacted purifying material, such as iron oxid, therefrom.

The side frame structures of the containers will be considered and described in pairs. First I shall describe the side wall which is shown in elevation at the right hand side of Fig. 2 of the drawings, it being understood that the opposing side wall is identical in construction. Each of these side walls comprises angle irons 4 at its opposite sides which are connected with each other by means of angle irons 5 and 6, the first being situated at the tops of the said angle irons 4 and the second a distance, as shown, above the lower ends of the said angle irons 4. In order to brace the connection between the said angle irons I have provided the two diagonal strips 7 and 8 which extend between diagonal corners of the frame forming the side walls of the container. The ends of said strips 7 and 8 are connected with the ends of said angle irons by means of the connecting plates 9. The bottom angle irons 6 are connected together by means of the transversely extending angle irons 10. The connection between the angle irons 6 and 10 is effected by means of the screw-threaded bolts and nuts 10^a. By removing the latter the said angle irons are discon-

nected. In Fig. 1 is illustrated in side elevation one of the other two side walls each of which comprises the angle irons 11 which are connected at top and bottom by means of the cross angle irons 12 and 13. These angle irons 12 and 13 are secured at their opposite ends to the angle irons 11 by means of the connecting plates 14, 15 and 17 designate braces extending diagonally between the corners of the frame constituting the walls. The construction of these two last mentioned side walls is the same.

It will be observed that the angle irons 11 are situated within the angles of the angle irons 4, the relative arrangement being clearly shown in Fig. 3 of the drawings. These side frame structures are secured or bound together by means of rods 18 which pass through holes 18^a in the outer edges of one of the flanges of each of the angle irons 4. The flanges containing these holes or openings are relatively wide as is shown in Fig. 3 of the drawings. It is apparent that when these rods are in place and when the nuts 19 are screwed into position thereon the several side frames constituting the supporting side walls of the container are securely but detachably bound together. Situated within these side frames is what may be termed a lining consisting of groups of slats secured together, one group constituting the bottom and the other groups, four of them, constituting the lining for the four sides of the container. These slats are connected together by means of rods 20, the slats in each group being separated from each other by means of separating sleeves or collars 21. It will be observed that the group of slats constituting the bottom of the container are first placed in position being supported on flanges 22 on the lower angle irons 6 and 13 and the crosswise angle irons 10 and that the lower ends of the respective groups of slats constituting the side portions of the container lining stand or rest upon the bottom slats. These slats being separated from each other permit the free passage therethrough of the gas so that it may freely enter and percolate through the purifying material 23, such as iron oxid, contained therein. The slats while being separated so as to permit the free passage therethrough of the gas which is to be purified and cleansed are sufficiently close together to securely hold and retain the iron oxid therein.

In order that the containers either filled or unfilled with the iron oxid or other purifying agent may be placed in position within the compartments of the inclosure or casing 2 each of the said compartments is provided with a door 25 hinged as at 26 to one edge of the top wall of such compartment. In Fig. 1 of the drawing the said door 25 is shown in full lines in open position and in dotted lines in closed position. When in closed

position it is adapted to be fastened around its edges by means of a toggle acting fastener 27 which is hinged at 28 to a bracket 29 depending from the sides of the casing. It may be noted that the casing or inclosure 2 when the door 25 is closed is hermetically sealed by means of a gasket around the edges so that it is gas tight.

The means shown in the accompanying drawing for introducing the containers into and removing the same from a compartment consists of a truck 30 which is adapted to be moved into and out of the compartment upon tracks 31. The truck 30 is provided with a platform 32 which is supported upon parallel links 33 which are pivotally connected with the truck 30.

In the position occupied by the platform 32, as illustrated in Fig. 1 of the drawing, the container is supported by means of the lower ends of the angle irons 4 and 11 upon the bottom wall of the casing or inclosure 2 and is not supported by the said platform. When it is desired, however, to lift the platform and consequently lift the container so as to remove the lower ends of the said angle irons 4 and 11 from the bottom of the casing or inclosure 2, the said platform is moved toward the front of the truck, that is, toward the left, having reference to Fig. 1 of the drawing. Such movement is accompanied by a simultaneous upward movement. Both of these movements are occasioned by means of a worm 35 having engagement with a worm gear 36 which in turn engages a gear upon a shaft 37 carrying a drum 38 upon which is wound a rope 40 having connection with the forward end of the platform 32. The worm 35 is rotated by means of a hand wheel 41. By rotating the latter to wind the drum 38 toward the left it will be understood that the rope 40 is wound up on the said drum so as to draw the platform 32 forward and thereby cause a lifting movement of the container together with any purifying material contained therein.

The container with the iron oxid or other purifying material therein having been lifted so as to raise the lower ends of the angle irons 4 and 11 from the bottom of the casing or inclosure the truck may be pulled forward along the track 31 to transport the container and the purifying material therein to such point as may be desired. Other suitable means than that shown may be employed for removing the container with the purifying material therein from the casing or inclosure. After the container with the purifying material therein has been removed from the casing or inclosure such material may be discharged readily by removing the nuts 19 from the screw-threaded ends of the rods 18, withdrawing the latter, disconnecting the cross angle irons 10 from the angle irons 6 and permitting or causing the several

sides of the container to fall outwardly away from the purifying material contained therein.

A container having therein a new charge 5 of iron oxid or other purifying material may be inserted into a compartment by means of the truck in an obvious manner.

It will be noted that the central portion of the rear of the truck as well as of the platform 10 32 is removed so that when the truck is moved into position underneath the container the opposite sides of the rear portions thereof pass upon opposite sides of the tubular outlet 45 constituting a duct through 15 which the gas passes from one compartment to another or from a compartment to a reservoir or tank.

The gas to be purified passes into a compartment through a gas inlet 46. Having 20 reached the compartment it passes between the slats upon the sides and bottom of the container as well as from the top into the iron oxid or other purifying material present in the container. It percolates through 25 this material and enters the tubular outlet 45 through a head 47 having openings therein which is situated within and is surrounded by the said purifying material. In the construction shown the head consists of 30 curved slats secured together and spaced from each other as shown. Preferably such head should be situated at a convenient distance below the center of the container in order to secure the best results. When so 35 situated substantially the same amount of gas enters the said head from all directions. If it were situated near the top of the iron oxid or other purifying material the tendency of the gas would be to follow the line 40 of least resistance and flow from the top downwardly through the upper portions of the purifying material into the said head with the result that a large proportion of the lower more solid and compacted portions of said material would not be used to 45 the extent necessary to secure available efficiency.

It will be observed that the tubular outlet 45 is provided intermediate its ends with 50 an annular flange 50 which is secured by means of bolts to the adjacent flanges of two of the angle irons 10 which extend between the side angle irons 6. It will be understood that one of these tubular outlets 55 is provided for each of the containers in each of the compartments of the casing or inclosure. The lower flanged end of each of these tubular outlets rests upon a compressible gasket 51 which is situated in an opening 52 formed in the bottom wall of a compartment of the casing or inclosure and which is supported in a seat 53 which surrounds an opening 54 formed in an outlet member 55 secured upon the lower side 60 of the casing or inclosure by means of rivets 65

56. The hole or opening 54 in the outlet member 55 is in alinement with the opening 52 and with the tubular member 45. The gasket 51 is of a height such that the lower end of the tubular member 45 contacts with 70 it before the lower ends of the angle irons 4 and 11 reach or contact with the bottom of the casing or inclosure 2. The result of this is that a considerable proportion of the weight of the container and the purifying material therein is supported upon the 75 said tubular member so that the latter presses firmly upon the gasket 51 to form a gas tight closure between the said gasket and the lower end of said tubular member. 80 The gas after it has percolated through the purifying material of the container passes out through a tubular member 45 and into the outlet member 55 and thence into an adjoining compartment through an opening 85 60 as shown in Fig. 2. The action of the purifying material contained in the container of the last mentioned compartment is identical with that just described. Instead of passing to a second compartment 90 and being further purified by purifying materials therein the gas may be conducted directly to a storage tank or reservoir ready for use or may be conducted directly to the point where it is to be used. 95

It will be understood that any other suitable means than that shown may be employed for inserting a container into and removing it from a compartment and also that instead of collapsing or taking it apart 100 for the purpose of discharging or removing the material therefrom it may be otherwise emptied, as by inverting it.

I claim:—

1. A container for gas or vapor purifying apparatus comprising a plurality of portions constituting the sides of the container structure, means for detachably securing said portions together, removable linings for said structure for holding the purifying material therein, said linings having openings to permit the passage therethrough of the gas or vapor to be purified. 105

2. In a gas or vapor purifying apparatus, the combination of a gas-tight casing or inclosure, a gas or vapor purifying material container arranged within said casing or inclosure, a gas receiving receptacle within the said container, a duct leading 110 120 from the said gas receiving receptacle, and means whereby the said duct is secured to portions of the structure of the said container.

3. In a gas or vapor purifying apparatus, the combination of a gas-tight casing or inclosure, a container for holding gas or vapor purifying material within the said casing or inclosure, means for detachably connecting the walls of the said container to each 125 130

other, linings for the said container having openings therethrough, a gas receiving conduit extending upwardly through the bottom of the said container and terminating 5 interiorly thereof, means for connecting the said conduit to the bottom of said container, an outlet from a compartment of the said casing or inclosure in which the said container is situated, and means whereby the 10 lower end of the said outlet forms a gas tight connection surrounding the said outlet.

4. In a gas or vapor purifying apparatus, the combination of a gas-tight casing or 15 inclosure, said casing or inclosure comprising one or more compartments each compartment having inlet and outlet openings, and each of said compartments having a door for closing and opening therein, a container 20 for holding gas or vapor purifying material within the said compartment or compartments, means whereby the said container may be inserted into and withdrawn through the opening closed by said door, and an outlet 25 conduit secured to the said container and having one end situated interiorly thereof and the other end being adapted to register with the outlet opening from a compartment.

30 5. In a gas or vapor purifying apparatus, the combination of a gas-tight casing or closure having inlet and outlet openings, a container for holding gas purifying material within a compartment of said casing or inclosure, a tubular gas outlet member secured to the bottom of said container and having one end projecting into the said container and the other end thereof projecting below the said container, an outlet member having 35 connection with the bottom of the said casing or inclosure, said outlet member having an opening registering with the outlet opening of the said compartment, said outlet member being provided with a seat surrounding said opening, a compressible 40 gasket situated in the said seat and within the outlet opening from said compartment and the lower end of the said tubular outlet member being adapted to contact with said gasket when the said container is situated in proper position within the said compartment.

45 6. In a gas or vapor purifying apparatus, the combination of a casing having a door for closing one side thereof and also having inlet and outlet openings, a container for holding the gas purifying material and means whereby said container may be inserted into and withdrawn from said casing or inclosure through the door-way closed by said door, a gas outlet member secured to the bottom of said container and having one end situated within the said container and the other end projecting below the same and 50 means whereby the jointure between the

lower end of the said outlet member and the outlet opening of the said casing is gas-tight, substantially as and for the purpose described.

7. A gas or vapor purifying apparatus 70 comprising a container for holding purifying material the walls of said container being detachable from each other, a perforated chamber situated in said container near its center, a duct leading from said 75 perforated chamber outwardly through a wall of said container, and means for securing the said duct to said wall.

8. In a gas or vapor purifying apparatus, the combination of a casing having inlet and 80 outlet openings and also being provided with a door, a container for holding gas purifying material adapted to be bodily inserted into and removed from said casing through the said door, said container having 85 openings through the walls thereof to permit the passage thereinto of a gas or vapor, a perforated gas receiving chamber situated within the said container preferably a short distance below the center thereof, a duct 90 leading from said chamber through a wall of said container, means for attaching said duct to said wall, and means for effecting a gas-tight connection between the outer end of said duct and the outlet opening of said 95 casing.

9. In a gas or vapor purifying apparatus, the combination of a casing having inlet and outlet openings and also being provided with a door, a container for holding gas 100 purifying material adapted to be bodily inserted into and removed from said casing through said door, said container having openings through the walls thereof to permit the passage thereinto of a gas or vapor, means for effecting the insertion and removal of said container into and from the 105 said casing, a perforated gas receiving chamber situated within the said container preferably a short distance below the center 110 thereof, a duct leading from said chamber through a wall of said container, means for attaching said duct to said wall, and means for effecting a gas-tight connection between the outer end of said duct and the outlet 115 opening of said casing.

10. In a gas or vapor purifying apparatus, the combination of a casing comprising a plurality of compartments each compartment having inlet and outlet openings 120 and each compartment being provided with a door, a container for holding purifying material adapted to be inserted into and withdrawn from a compartment through said door, the walls of said container having openings therethrough, a gas receiving chamber situated in said container a short distance below the center thereof, a duct leading from said gas receiving chamber through a wall of a compartment, means 125 130

for attaching said duct to said wall, means
for forming a gas-tight connection between
the outer end of said duct and the outlet
opening of said compartment, and means
5 for conducting the gas which flows out
through said duct to an adjoining compart-
ment, substantially as described.

In testimony that I claim the foregoing
as my invention I have hereunto signed my
name this 25th day of June, A. D. 1915.

CHARLES H. CLOWER.

In the presence of—

GEORGE P. SHEPHERDSON,
REES C. ROBERTS.
